UNITED STATES PATENT OFFICE.

ALFRED BLONDEL, OF TOURNAI, BELGIUM.

FLOATING AND LIFTING BRIDGE.

1,367,115.

Specification of Letters Patent.

Patented Feb. 1, 1921.

Application filed May 27, 1919. Serial No. 300,153.

To all whom it may concern:

Be it known that I, ALFRED BLONDEL, a subject of the King of Belgium, residing at Tournai, in the Kingdom of Belgium, have 5 invented certain new and useful Improvements in Floating and Lifting Bridges, of which the following is a specification.

My invention relates to improvements in floating and lifting bridges of that class in 10 which balancing floats immersed in watertight shafts are coöperating with auxiliary means adapted to secure the complementary motive power which is necessary to operate the bridge, that is to say, to effect its ascent 15 and descent.

One object of my invention is to provide for a greater security than hitherto attained in the operation of the bridge.

Another object of my invention is to reduce 20 the costs of construction of bridges of this class, and a further object is to provide simple and reliable means for the control of the tightness of the floats.

With these objects in view, my invention 25 essentially consists in special combinations and arrangements of parts which will be hereinafter fully described and pointed out in the appended claims.

Referring to the annexed drawing:

30 Figure 1 shows diagrammatically partly in section a lifting bridge constructed according to my invention,

Fig. 2 is a top view of the bridge corresponding to Fig. 1.

35 In these figures *a* is the movable part of a lifting bridge, *b* the floats coöperating with said movable part and which are immersed in water-rooms *p*.

In lifting bridges of this class as hitherto 40 constructed, the floats *b* were generally used to balance more or less the weight of the movable part of the bridge, auxiliary means (such as a float having variable buoyancy or any other suitable motive power) being 45 used for raising and lowering the bridge.

According to my invention, on the contrary, the floats *b* which are completely immersed in the water contained in suitable rooms *p*, are dimensioned in such a manner 50 as to possess an excess of lifting power or buoyancy, having consequently the tendency to hold the movable part of the bridge in its uppermost position, whereas the auxiliary means secures the necessary force to retain 55 the movable part in its lowest position.

The floats *b* which are preferably elliptical

in shape, instead of being arranged vertically in water-tight shafts as is generally the case, are arranged horizontally in the water-rooms *p* extending longitudinally on 60 both sides of the river. These water-rooms can be constructed very easily by dredging the bed of the river so as to provide for the necessary depth and then constructing walls *g* in a well known manner.

65 *r* is the auxiliary motor such as an electric-motor coöperating with cables *s* which are suitably guided and attached to the walls of the water-rooms *p* or to any other points of the river-bank; the pull of these cables *s* 70 which is produced for example by the rotation of a drum to which the cables are attached at one end and which is driven by the motor, balances the excess of buoyancy of 75 the floats *b* and holds the movable part *a* of the bridge in its lowest position in which it rests upon suitable bases or beds at the upper ends of the wharf walls.

The floats *b*, which necessarily possess 80 great dimensions can be connected to the movable part of the bridge by the aid of tubes *t* in which a ladder *u* can be arranged to enable the inspection of the floats. Further in order to facilitate the control of the tightness of the floats, these floats are 85 preferably connected by a pipe to a pump, driven by the auxiliary motor *r* or by any other suitable motor, said pump maintaining in the floats a given pressure such as for instance a pressure of about two atmospheres. 90 In this case, however, the tubes *t* must be evidently closed at their upper part and the floats can be provided with a safety-valve preventing any excess of pressure. In these 95 conditions any defect of tightness of the floats is immediately disclosed either on account of the fall of pressure or on account of the ascent of air bubbles to the surface of the water.

In order to avoid with certainty any wedging 100 of the floats against the walls of the rooms *p*, the floats can be provided at the place of their greatest diameter, with rollers *v* adapted to roll along said walls in case of contact; this arrangement can be advantageously combined with the use of oscillating floats that is to say of floats pivotally connected to the movable part of the bridge. This construction is particularly suitable in 105 lifting bridges, the movable part of which 110 is pivotally mounted at one end on the wharf wall and in which the floats necessarily move

to some extent in a horizontal direction during the operation of the bridge, the rollers contacting alternately with only one of the walls of the water-rooms in which the floats are immersed.

Independently of the great security of operation of a lifting bridge constructed as described, it is to be noted, that in case of failure of the motor, the bridge remains 10 in its uppermost position without interfering with the traffic on the river or channel.

Another important advantage of the construction as described consists in the fact that the digging of shafts of great depth 15 can be dispensed with, this operation being replaced by a simple dredging operation.

With regard to the operation of the bridge it will be observed that the lifting bridge, constructed according to my invention, is 20 like a kind of captive bridge (by analogy with a captive balloon) and that the floats, if they are emerging from the water, act as a brake, the speed of ascent of the movable part of the bridge which is maximum at 25 the beginning of the ascent, being reduced gradually in proportion to the degree of emersion of the floats until a state of equilibrium corresponding to the uppermost position of the bridge will be attained.

30 What I claim is:

1. In a lifting bridge, in combination with the movable part of the bridge and piers, floats coöperating with said movable part, the buoyancy of said floats being greater 35 than that necessary to balance the weight of the movable part and auxiliary means connected between the movable part of the bridge and the piers and operative to retain the movable part of the bridge in its lowest 40 position against the action of the floats.

2. In a lifting bridge in combination with the movable part of the bridge and piers, floats coöperating with said movable part, the buoyancy of said floats being greater 45 than that necessary to balance the weight of the movable part, water-rooms arranged on both sides of the river, and in which the floats are immersed, the said floats being horizontally arranged in said rooms, an aux-

iliary motor, and means controlled by the 50 motor and connected between the piers and movable part of the bridge for lowering the said movable part against the action of the floats.

3. In a lifting bridge, in combination with 55 the movable part of the bridge, a float supporting the movable part of the bridge at each end, the buoyancy of said floats being greater than that necessary to balance the weight of the movable part of the bridge, 60 a water-room on each side of the river, the floats being immersed and horizontally arranged in said water-rooms, means connecting the floats to the movable part of the bridge, the said means giving access to the 65 floats, an auxiliary motor mounted on the movable part of the bridge and cables connected at one end to said motor and at the other end to points of the river bank, whereby the movable part of the bridge may be 70 lowered and held in its lowest position by the pull of the motor on the cables.

4. In a lifting bridge, the combination 75 with the movable part of the bridge, a plurality of floats supporting the movable part of the bridge, the total buoyancy of said floats being greater than that necessary to balance the weight of the movable part of the bridge, water rooms arranged on both sides of the river and in which the floats are 80 immersed, the said floats being horizontally arranged in the said water-rooms, tubes connecting the floats to the movable part of the bridge, a ladder in each of said tubes, an auxiliary motor mounted on the movable 85 part of the bridge, cables connected at one end to said motor and at the other end to points of the river bank, whereby the movable part of the bridge is held in its lowest position by the pull of the motor on the 90 cables, and means for controlling the tightness of the floats.

In testimony whereof I have affixed my signature in presence of two witnesses.

ALFRED BLONDEL.

Witnesses:

ROBINSON RILEY,
PETER PETERSEN.
